UNITED STATES PATENT OFFICE.

JOHN PIERCE, JR., OF SOUTH NORWALK, CONNECTICUT, ASSIGNOR OF ONE-HALF TO
DICKINSON S. CUMMINGS, OF STAMFORD, CONNECTICUT.

BOILER-UNIT-ASSEMBLING RACK.

1,350,236.

Specification of Letters Patent. Patented Aug. 17, 1920.

Original application filed February 13, 1920, Serial No. 358,513. Divided and this application filed June 3, 1920. Serial No. 386,394.

To all whom it may concern:

Be it known that I, JOHN PIERCE, Jr., a citizen of the United States, and a resident of South Norwalk, in the county of Fairfield and State of Connecticut, have invented 5 Boiler-Unit-Assembling Racks, of which the following is a specification.

The invention herein disclosed and claimed 10 is divided from my original copending application for steam boilers, Serial No. 358,513, filed February 13, 1920.

In the original application a steam boiler 15 is claimed and embodies sections or units, each of which includes a vertical header and horizontally U-shaped circulating tubes 20 whose legs are arranged at an angle to each other. The present invention is designed principally to hold the header and securely clamp the tubes in their proper position 25 with respect to the header until the same have been welded thereto.

The invention further provides a boiler 30 unit assembling rack including clamping elements adjustable parallel to the header so that each of the U-shaped tubes will be held in proper position until the weld between the individual tubes and header is completed.

With the above and other objects as may 35 become apparent from the following disclosure, the invention consists in the novel combination of elements, construction and arrangement of parts, operation and specific features to be hereinafter enlarged upon 40 and recited in the subjoined claims, the invention being illustrated in the accompanying drawing, wherein,

Figure 1 is an elevation of the rack having 45 the header and one of the circulating tubes in position for welding;

Fig. 2 is a vertical sectional view taken on line 2-2 of Fig. 1;

Fig. 3 is a horizontal sectional view taken 50 on line 3-3 of Fig. 1;

Fig. 4 is a detail view illustrating the ends of the tube being electrically welded to the header; and

Fig. 5 is a detail view showing the tube and header after the weld has been completed.

Referring in detail to the drawing, where 55 in corresponding parts are designated by corresponding characters of reference through-

out the several views, the numeral 5 designates a pair of horizontal parallel members 55 connected at one end by a vertical bar 6. A pair of vertical bars 7 extend from the opposed face of the bars 5 adjacent their ends and are of less width than these bars 5 and against which the circulating tubes 60 being assembled with the header rests as is more clearly illustrated in Figs. 2 and 3. The ends of the bars 5 opposite the ends with which the bars 6 are connected are cut away as at 8 and formed with a semi-circular recess 9 adapted to embrace the vertical header designated at H. A clamping block 10 is provided for each cut away face and is formed with a semi-circular recess 11 coinciding with the recess 9 and embracing the 65 header H, the clamping blocks being detachably held in clamping engagement with the header by fastenings 12 passing transversely through the bars 5 and blocks 10.

Secured to the bars 5 at opposite sides 70 thereof and adjacent their opposite ends are pairs of guide bars 13. Disposed between each pair of guide bars 13 and adapted for vertical adjustment therebetween and each having one face resting against one of the 75 guide bars 13 is a clamping block 14 having its outer face beveled inwardly from its upper end so that this face will engage both legs of a U-shaped circulating tube arranged at an angle to each other as illustrated in 80 Fig. 2. A U-shaped yoke 15 is slidably mounted upon one of each pair of guide bars 13 and each has its extremities attached to the opposite vertical face of the clamping blocks 14. A set-screw 16 is carried by each 85 of the U-shaped yokes and is adapted to engage its respective bar 13 at any desired point to retain the clamping box 14 in adjusted position.

In assembling the U-shaped tubes with 90 the header, the lowermost tube is arranged between each pair of arms 13, with the legs resting against the opposite face of the vertical bars 7 and the lowermost leg resting against the lower horizontal bar 5, this being 95 fully shown in Fig. 2. The clamping blocks are then adjusted to engage both legs of the U-shaped tube and thereby clamp the same in position for welding. After the lowermost tube has been assembled the 100 blocks 14 are adjusted vertically and the 105

next tube placed in position as the one previously described and the clamping blocks engaged thereagainst.

It is to be understood that the form of my invention herein shown and described is to be taken as a preferred example of the same, and that various changes in the shape, size and arrangement of parts may be resorted to without departing from the spirit of the invention or the scope of the subjoined claims.

Having thus described my invention, what I claim as new and desire to secure and protect by Letters Patent of the United States is:

15 1. In a work holder, a frame, means carried by the frame for supporting an element at one end of the frame, pairs of bars secured to the opposite faces of the frame and between which, elements, each including a pair of legs to be assembled with the first mentioned element, are arranged, and vertically adjustable blocks mounted between each pair of bars and adapted to engage both legs of the element to clamp the 20 same in proper position with respect to the first mentioned element while said legs are being secured thereto.

2. In a work holder, a frame, means at one end thereof for supporting an element, 30 pairs of parallel bars secured to opposite faces of the frame and between which, elements, each including parallel legs arranged at an incline with respect to each other, are adapted to be arranged and with the ends 35 thereof in position for attachment to the first mentioned element, and clamping blocks vertically adjustable between each pair of bars and each having their outer faces beveled to engage both legs of said 40 element to clamp the same in position while the ends are being secured to the first mentioned element.

3. In a work holder, a frame, means at one end thereof for supporting an element, 45 pairs of parallel bars secured to opposite faces of the frame and between which, elements, each including parallel legs arranged at an incline with respect to each other, are adapted to be arranged, and with the ends 50 thereof in position for attachment to the first mentioned element, clamping blocks arranged between each pair of bars and ad-

justable longitudinally of the same and each having one face beveled and adapted to engage both legs of said element, a U-shaped member carried by each block and adjustable on one of each pair of bars, and fastenings for retaining the U-shaped members at any point on the bars.

4. In a boiler unit assembling rack, a rectangular frame, means for supporting a boiler header in one end of the frame, parallel bars disposed in the frame, pairs of bars extending parallel of the first mentioned bars and secured to opposite ends 65 of the frame and between which, horizontally disposed boiler circulating tubes, each having its legs at an angle with respect to each other, are adapted to be arranged in position for attachment to 70 the header and disposed upon the first mentioned upper face of the parallel bar, and clamping elements adjustably mounted between each pair of parallel bars and having an obliquely disposed face for engagement 75 with the legs of the tube to hold the same against the first mentioned bars and the pair of parallel bars while the ends thereof are being secured to the header.

5. In an apparatus for assembling boiler 80 sections including a frame, means for supporting a header of the boiler at one end of the frame, pairs of parallel bars detachably secured to the opposite faces of the frame, one of each pair of bars constituting a rest 85 for the boiler circulating elements being assembled with the header, and vertically adjustable members on the opposite bar of each pair adapted to bear against the circulating element being assembled to retain the 90 same in position for welding to the header.

6. In an apparatus for assembling boiler sections, each including a header and U-shaped pipes the legs of which are arranged at an angle to each other, including 95 a rectangular frame, means supporting the header at one end of the frame, parallel bars secured to the frame, and vertically adjustable blocks on one bar of each pair and having their outer faces beveled, the 100 blocks being adapted to engage the tube being assembled with the header to retain the same in proper position for welding.

JOHN PIERCE, JR.
